ELECTRIC CIRCUIT BREAKER

William E. Paul, Schenectady, N. Y., assignor to
 General Electric Company, a corporation of
 New York

Application May 27, 1937, Serial No. 145,057

15 Claims. (Cl. 200—150)

My invention relates to electric circuit breakers, more particularly to high voltage circuit breakers of the oil blast type wherein pressure generated by arcing at one part of the circuit is utilized for directing a blast of arc-extinguishing fluid through an arc at another part of the circuit.

It has been proposed in circuit breakers of the aforesaid type that the contact structure be arranged so that two arcs in series are progressively formed. The first or pressure generating arc has a substantially constant length and is utilized to cause a blast of oil or other arc-extinguishing liquid at the subsequently formed main arc for interrupting the same. With this arrangement there may be difficulty in interrupting with equal facility comparatively small and heavy short circuit currents by reason of the substantially fixed length of the pressure generating arc. This is due to the fact that insufficient pressure may be generated for interrupting a low current arc, assuming of course that the contact separation is suitable for large currents.

Another limiting factor in this design is that the speed of operation is somewhat retarded by the movement or "wipe" of the contact structure prior to actual arc formation and the interrupting action of the blast. That is, a certain wipe takes place even before formation of the pressure generating arc, and a subsequent wipe or following action of the contacts occurs prior to formation of the main arc which is subject to the oil blast. Where the interruption of high voltage alternating current power circuits within two or three cycles is required, these factors are very important in determining the ultimate operating speed of the breaker.

The principal object of my invention is the provision of an improved high voltage circuit breaker of the oil blast type that is efficient and reliable particularly as regards arc interruption throughout the entire rated interrupting range of the breaker, and is also capable of high speed circuit interruption.

My invention will be more fully set forth in the following description referring to the accompanying drawing, and the features of novelty which characterize my invention will be pointed out with particularity in the claims annexed to and forming a part of this specification.

Referring to the drawing, the single figure thereof is an elevational view, partly in section and partly diagrammatic, of a high voltage electric circuit breaker embodying the present invention.

The circuit breaker illustrated is of the high voltage oil-blast type and comprises an insulating casing or fibre cylinder 1 forming a pressure-confining chamber containing a suitable arc-extinguishing liquid 2, such as oil for example, in which are immersed the relatively movable contacts. The breaker contact structure comprises a fixed or terminal contact 3 electrically connected at 4 to the metallic terminal housing 5, a pivoted arcing contact 6 normally biased by a spring 7 into contact engagement with the fixed contact 3, a stationary intermediate contact 8 electrically connected at 9 to the intermediate contact 6, and a movable rod contact 10 which is guided for reciprocal movement through the bottom plate 11 of the breaker casing. The breaker as shown is in the open-circuit position, the contacts 6 and 10 being insulated from each other by the insulating oil in the casing. The contact rod 10 is suitably operated between its closed circuit position, wherein it engages in butt contact the intermediate contact 8, and the open circuit position by an operating mechanism generally indicated at 12.

The power circuit is completed in the closed position of the breaker through the terminal structure 4—5, coacting contacts 3 and 6, intermediate contact structure 8—9, and the contact rod 10 which is suitably connected to the other terminal. When the rod 10 is lowered to open the circuit, an arc is immediately formed in the insulating oil between the contacts 6 and 10, thereby generating pressure depending on the arc current within the breaker casing.

The upper part of the casing 1 is provided with a pressure relief passage 13 within which the pivoted contact 6 is located so as normally to close the passage. Accordingly, when sufficient arc pressure builds up within the lower part of the casing, the contact 6 is pivoted clockwise against the bias of spring 7 thereby opening the circuit at that point. Concurrently a blast of oil is released through the chimney-like passage 13 to exhaust into the upper housing 5 where it is collected and subsequently returned to the arc chamber.

Accordingly, the arc formed between the contacts 3 and 6 is traversed by a high velocity oil blast and the circuit is interrupted at that point. It will be apparent that the tension of the spring 7 may be adjusted so that the contact 6 will open only when the desired arc pressure is generated within the casing. In this manner even comparatively low current arcs are effectively interrupted since the arc pressure is substantially 50 55 60 65 70 75 80 85 90 95 100 105 110 115 120 125 130 135 140 145 150 155 160 confined until it builds up to the desired blast value. Interruption of the arc at the contact 6 necessarily extinguishes the series arc at the contacts 8, 10 so that an isolating gap in oil between these contacts is effective to prevent re-establishment of arcing. The contact 6 therefore may return to its initial position under bias of the spring 7.

In order, however, to prevent premature closing of the contact 6 a suitable retarding device, generally indicated at 14, is operatively connected to the contact 6 through a pivoted lever 15 and an insulating link 16 connected at 17 to an extension of the contact 6. Any suitable retarding or escapement device may be employed, a dash-pot 18 being illustrated by way of example. When the contact 6 is opened the dash-pot plunger is raised without resistance, the opposite stroke, however, retarding the reclosing movement of the contact 6. In this manner, the arc gases etc., tending to decrease the dielectric strength of the oil, can escape from the region of the contacts 8—10 before reclosure of contact 6, thereby minimizing the possibility of reignition of the arc.

In the case of heavy short circuit currents the arc pressure, particularly where the arc is lengthened as by looping under the influence of magnetic forces, may be so great as to damage the breaker. For the purpose of controlling the arc pressure in the case of heavy currents, there is provided means for short-circuiting the initial part of a heavy current arc, thereby shortening the same, so that the pressure is correspondingly decreased. To this end a conducting sleeve or ring is fixed with respect to and surrounds the contact portion of the intermediate contact 8. The member 19, which is larger in diameter than the contact rod 10 so that no actual contact is made between the two, is provided with laterally disposed pressure relief vents 20 and in the present instance is electrically connected to the contact 8.

It shall be understood that the conducting ring is not necessarily electrically connected to the contact 8 and that under certain conditions a small insulating gap may separate the same. A heavy current arc by reason of the magnetic forces tending to cause looping or bowing will shift laterally to the surrounding conductor and strike between the lower edge of the member 19 and the contact rod 10 as indicated at 19', thereby shortening the length of the arc and decreasing the arc pressure correspondingly. In the case of light currents, the arc tends to strike directly between the contacts 8 and 10 so as to utilize the maximum arc length for building up the blast pressure.

It will be apparent that the conducting ring 19 may be formed in any suitable manner, such as for example like a squirrel cage, the spacing between the bars in this case serving as pressure relief openings for the gas pressure generated when the contacts separate. This gas pressure may otherwise produce an abnormal accelerating effect on the rod 10.

A further device is preferably also employed for regulating the arc pressure due to heavy load or short-circuit currents. This comprises a current responsive control mechanism generally indicated at 21 for determining the length of stroke of the contact rod 10 under certain conditions. Since the arc pressure is dependent inter alia on the length of the arc, the opening travel of the contact 10 is shortened as the current increases.

To this end the contact 10 which is operated

in a manner presently described by the floating lever 22 of the operating mechanism 12 is connected in series with a conductor loop 23. The opposite sides of the loop are secured with respect to a pair of insulating jaws 24 and 25 pivotally connected at 26. The jaw 24 is secured to a fixed mounting at 27, and the relatively movable jaw 25 is operatively connected by means of a link 28 to a slidably mounted stop member 29 adapted to coact with the lower end of the contact rod 10. A compression spring 30 bearing between a fixed guide 31 and the jaw 25 tends to maintain the conducting loop in a compressed position as indicated.

When the floating lever 22 is rotated under bias of the main operating spring 32 so as to cause downward or opening movement of the contact 10 the current traversing the circuit creates magnetic forces tending to expand the loop 23 in a manner well known in the art. The tension of the spring 30 bears a predetermined relation to the magnitude of the current so that only in response to moderately heavy currents is the stop member 29 moved by the magnetic forces acting against the bias of spring 30.

Assuming now that a moderately heavy load current is to be interrupted, the loop 23 is expanded by the magnetic forces so as to slide the stop member 29 a short distance toward the right as viewed so that the step 29' is beneath the insulating end portion 10' of the contact rod. The opening stroke of the contact is thereby reduced by a predetermined amount and the arc correspondingly shortened. If a heavy short circuit is involved the member 29 will be moved so that the step 29'' is beneath the contact end 10', thereby further shortening the arc.

It will be apparent that any desired number of steps may be used in this connection, or as a simple alternative the stop member may be wedge-shaped so as to limit the arc length more closely with respect to the current to be interrupted.

Referring more particularly to the operating mechanism 12 which may be of any suitable high speed trip-free type, the floating lever 22 is pivotally connected at one end to the armature 33' of a tripping magnet 33 and at the other end is connected to the contact rod 10 through a link 34. The central part of the lever coacts through 50 a guide member 35 with an operating arm 36 of a suitable power device.

It will therefore be apparent that the lever 22 can be pivotally rotated about its pivotal connection with the armature 33' to cause upward or circuit-closing movement of the rod 10 when the arm 36 of the power device is rotated clockwise.

The guide member 35 comprises a cylinder guided for vertical reciprocal movement at 37 and at 38. For the purpose of allowing a limited amount of "wipe" between the power device and the operating mechanism the cylinder 35 has mounted therein a spring buffer arrangement 39 for coacting with the roller 40 of the power device.

The cylinder 35 is connected to the lever 22 through a pin and slot connection 41—42, the slot 42 in the lever 22 being slightly elongated for permitting pivotal movement of the lever with respect to the tripping magnet 33. A compression spring 43 acting between the guide 35 and lever at 43' is utilized for biasing the lever toward the right so as to center the magnet end of the lever during the resetting operation. At the end of the operating stroke the spring buffer 39 takes up the additional "wipe" of the mecha-

nism formerly assumed by the contact structure. In this manner the connections between the floating lever 22, which is directly controlled by the tripping magnet 33, and the movable contact structure can be rigid so that opening of the circuit immediately upon release of the floating lever is effected by the spring 32.

The operation of the tripping magnet 33 is well known in the art and can be readily understood from the drawing, the tripping coil 44 for causing release of the armature 33' from the permanent magnet 33 being energized from the conventional line current transformer at 44'.

The operation of the mechanism 12 is as follows: In the open circuit position shown the magnet 33 is reset so that the armature 33' constitutes a fixed pivot for the floating lever 22. When the power device at 36 is actuated, the guide member 35 is raised and the lever 22 rotated clockwise about the armature 33' against the bias of spring 32 so as to close the breaker at the contacts 8-10. When the breaker is tripped in response to overload or short-circuit, the tripping coil 44 of the magnet releases the armature 33' so that floating lever 22 is rotated rapidly about its central pivot at 41 in counter-clockwise direction by the opening spring 32. Resetting of the mechanism is effected by simply lowering the arm 36 of the power device so that the armature 33' again engages the magnet. It will be apparent that the mechanism is trip-free in operation since at any time during the closing stroke the spring 32 is effective to rotate the lever 22 about its central pivot pin upon release of the armature 33'.

The "wipe" connection at 39 it will be noted is between the power device and the lever 22 so that release of the armature 33' is effective to cause instant separation of the coacting butt contacts 8-10 which have no "wipe" contact. Accordingly, the pressure-generating arc is instantly formed after the tripping impulse and the pressure created for interrupting the arc is generated at the earliest possible moment.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States, is:

1. An electric circuit breaker of the oil blast type comprising a pressure-confining casing containing an arc-extinguishing liquid and relatively movable contact structure adapted to form two breaks in series in said liquid including a movable pivoted contact normally biased toward closed circuit position, said pivoted contact normally closing a pressure relief passage in said casing, an intermediate relatively fixed contact and a second movable contact coacting with said fixed contact, the arc pressure generated in said casing at the break between said fixed and second movable contact being utilized to open said biased contact and drive an arc-extinguishing liquid blast through said passage and the arc at that point.

2. An electric circuit breaker of the oil blast type comprising a pressure-confining casing containing an arc-extinguishing liquid and relatively movable contact structure immersed in said liquid including a movable contact normally biased toward closed circuit position, means for generating arc pressure in said casing for causing

opening of said biased contact and an arc-extinguishing liquid blast through the arc at that point, and retarding means for delaying reclosure of said movable contact after extinction of said arc.

3. An electric circuit breaker of the oil blast type comprising a pressure-confining casing containing an arc-extinguishing liquid, relatively movable contact structure adapted to form two breaks in series in said liquid including a movable contact normally biased to closed circuit position, an intermediate relatively fixed contact electrically connected to said biased contact and a movable rod contact coacting with said fixed contact, the arc pressure generated at the break between said fixed and rod contacts being utilized to open said biased contact and drive an arc-interrupting liquid blast through the arc at that point, and a retarding device operatively connected to said biased contact for permitting free opening movement thereof and for retarding reclosure thereof for decreasing the possibility of reestablishment of arcing between said fixed and rod contacts.

4. An electric circuit breaker of the oil blast type comprising a pressure-confining casing containing an arc-extinguishing liquid, said casing being vertically positioned and having a chimney-like exhaust passage at the upper part thereof, and relatively movable contact structure adapted to form two breaks in series in substantially vertical alignment in said liquid including a movable contact normally biased to closed circuit position, said contact being positioned in said passage so as to close the same in said closed circuit position, and means at one of said breaks for creating arc pressure in the lower part of said chamber for opening said biased contact and driving an arc-extinguishing liquid blast through said passage and the arc at that point.

5. An electric circuit breaker of the oil blast type comprising a pressure-confining casing having an exhaust passage and containing an arc-extinguishing liquid, and relatively movable contact structure adapted to form two breaks in series in said liquid including a pivoted contact normally biased toward closed circuit position and located in said exhaust passage to close the same, opening of said pivoted contact forming a break in the circuit substantially transversely of said passage, a relatively fixed rigidly mounted contact electrically connected to said pivoted contact, and a movable rod contact adapted to abut said fixed contact, opening movement of said rod contact causing instantly a break at said fixed contact for generating in said chamber arc pressure for opening said biased contact and driving an arc-extinguishing liquid blast through said passage and the arc at said first-named break.

6. An electric circuit breaker of the oil blast type comprising relatively movable contact structure adapted to form two breaks in series in an arc-extinguishing liquid, means for directing the pressure generated at one of said breaks so as to cause a blast of said liquid at the other break for interrupting the circuit, and means for controlling the arc pressure at said generating break including conducting structure substantially surrounding said generating break adjacent the point of formation thereof so that a heavy current arc is short circuited in part by said conducting structure so as to shorten said arc.

7. An oil circuit breaker including relatively movable contact structure separable in an arc-

- extinguishing liquid to cause generation of pressure for interrupting the circuit, and means for controlling said arc pressure comprising a generally cylindrical conducting structure substantially surrounding said arc adjacent the point of initial formation thereof, said structure being concentrically located with respect to the central axis of said contact structure so as to be spaced from said arc at low current values and 10 short circuit the same in part at comparatively large current values.
8. An electric circuit breaker comprising relatively movable contact structure immersed in an arc-extinguishing liquid, said contact structure 15 adapted to form a pressure-generating break for causing an arc-interrupting liquid blast, and means for controlling the arc pressure comprising a conducting cylinder electrically connected to a part of said contact structure and substantially surrounding the arc at the point of initial formation thereof, said cylinder being open at one end for receiving another part of said contact structure and being in spaced concentric relation thereto so that said arc is short circuited 20 in part by said conducting cylinder at comparatively large arc currents.
9. An electric circuit breaker of the oil blast type comprising a fixed contact and a relatively movable rod contact positioned within a pressure-confining casing and immersed in an arc-extinguishing liquid, a conducting cylinder connected to said fixed contact so as to surround in concentric relation the contact end of said rod contact in closed circuit position, said cylinder having pressure relief openings and being spaced from said contact rod so as to short circuit the enclosed part of the arc at comparatively heavy arc currents.
10. An electric circuit breaker comprising relatively movable contact structure, and electromagnetic means responsive to the magnitude of the current to be interrupted for determining the degree of separation of said contact structure.
11. An electric circuit breaker comprising fixed and relatively movable contacts arranged to form two breaks in series, the arc pressure generated upon separation of said contacts at one of said breaks being utilized for interrupting the circuit at the other of said breaks, and means coacting 50 with the movable contact structure at said pressure generating break responsive to the magnitude of the current to be interrupted for limiting the opening stroke of said contact structure so as to decrease the arc pressure at comparatively high currents.
12. An electric circuit breaker comprising relatively movable contacts, the arc pressure gener-

ated upon separation of said contacts being utilized for interrupting the circuit, and electromagnetic means responsive to the magnitude of the current to be interrupted for blocking the separation of said contact structure at a predetermined point. 5

13. An electric circuit breaker comprising relatively movable contact structure, the arc pressure generated upon separation of said contact structure being utilized for interrupting the circuit, and arc pressure control means including a conductor in series with the circuit normally positioned in the form of a compressed loop, resilient means biasing said loop toward said compressed position and a member adapted to 15 coact with said contact structure for limiting the degree of separation thereof, said member being operatively connected to said loop so that expansion of said loop in response to comparatively large currents causes movement of said member 20 toward a position for limiting the aforesaid contact separation.

14. An electric circuit breaker comprising relatively movable contact structure adapted to coact in substantially non-yielding engagement for facilitating quick separation thereof and means for effecting high speed separation of said contact structure including an operating member having a non-yielding operative connection with a movable part of said structure, means for biasing 30 said member to open circuit position, a tripping device directly connected to said member for restraining the member in closed circuit position, actuating means for moving said member against said biasing means to closed circuit position, and 35 resilient means interposed between said actuating means and said member for permitting a limited over-travel of said actuating means upon contact engagement.

15. An electric circuit breaker comprising relatively movable contacts, a floating lever operatively connected at one end to the movable contact, a tripping device coacting with the opposite end of said lever, said lever being pivotally mounted with respect to said device and movable 45 contact, actuating means coacting with said lever intermediate the ends thereof for closing said movable contact, a reciprocally guided resilient connection between said lever and actuating means, said lever having a limited lateral movement with respect to said guided connection for permitting rotation about said tripping device, and spring structure for biasing said lever toward open circuit position about said guided connection in response to actuation of said tripping device. 50 55

WILLIAM E. PAUL.
